UNITED STATES PATENT OFFICE.

ERNST G. K. ANDERSON, OF CHICAGO, ILLINOIS, ASSIGNOR TO ANDERSON ELECTRIC & EQUIPMENT CO., OF CHICAGO, ILLINOIS, A CORPORATION OF ILLINOIS.

LAMP FOCAL ADJUSTMENT.

1,389,571.

Specification of Letters Patent. Patented Sept. 6, 1921.

Application filed October 31, 1917. Serial No. 199,412.

To all whom it may concern:

Be it known that I, ERNST G. K. ANDERSON, a citizen of the United States, and a resident of Chicago, in the county of Cook and State 5 of Illinois, have invented certain new and useful Improvements in Lamp Focal Adjustment; and I do hereby declare that the following is a full, clear, and exact description thereof, reference being had to the accompanying drawings, and to the characters of reference marked thereon, which form a part of this specification.

This invention relates to improvements in means for focal adjustment of electric lamps 15 with respect to reflectors, and the invention is herein shown as applied to head light lamps used on vehicles, and sometimes known as spot lamps.

The purpose of the invention is to provide 20 a simple and reliable means for adjusting the lamp with respect to the focal center of the reflector and for maintaining the lamp in adjustment.

Another object of the invention is to provide 25 a device of this character wherein the adjustment of the lamp may be effected from the exterior of the lamp structure without the necessity of dismembering any portion of said structure.

The invention consists in the combination and arrangement of the parts as shown in the drawings and described in the specification, and is pointed out in the appended 30 claims.

As shown in the drawings:

Figure 1 is a rear view of a lamp equipped with my improvements.

Fig. 2 is a horizontal sectional view of the lamp, with parts shown in elevation.

Fig. 3 is a front elevation of the adjusting member of the device and parts associated therewith.

Fig. 4 is a perspective view thereof.

Fig. 5 is a perspective view of said adjusting device and its guide casing or neck.

Fig. 6 is a fragmentary rear perspective view of the reflector, showing the parts thereon which coöperate with the adjusting member.

Fig. 7 is a perspective view of a cap or covering for the guide casing or neck.

As shown in the drawings, 10 designates, as a whole, the lamp casing, 11 the reflector, and 12 designates the lens which is supported across the front open end of the casing.

The lamp structure is herein shown as of that type illustrated in my U. S. Letters Patent Number 1,309,678, granted July 15, 1919, embracing a casing 14 to receive a take-up device for the conductor cord 15 that leads 60 to the lamp. Said casing is fixed to a support, as the upright post 16 of a wind shield frame, as by means of a suitable clamp 17. The lamp is supported from said casing by a bracket arm 18 on which the lamp casing is 65 rotatively mounted to swing in vertical direction, and which arm is rotatively and detachably mounted on the casing to swing in a horizontal direction in the manner illustrated in the aforesaid prior application. 70

20 designates an electric lamp, the base 21 of which is fixed in any suitable manner, as by means of the well-known bayonet joint, in a socket sleeve 22. Said socket sleeve fits within and is adapted to slide endwise of a 75 flange or nipple 24 that is formed integral with and extends rearwardly from the rear wall of the reflector at the axis thereof. Extending transversely through said socket sleeve, and at a distance from each side 80 thereof, is a pin 26. As herein shown said pin extends also through a disk 27 which fits closely in the rear end of said sleeve and carries the terminals 28 (Fig. 6) to which one wire 29 of the conductor cord 15 is connected; said terminals engaging contacts on the rear end of the lamp base in a known manner. 85

The other wire 30 of the conductor cord extends into and is connected to a switch device, designated as a whole by 31, that is operated by upper and lower push buttons 32. Said switch device is inclosed in a casing 33, which constitutes the neck of the lamp casing and which is fitted within a central opening in the rear wall of said lamp casing and extends rearwardly therefrom and, as herein shown, a distance inside said wall. Said neck constitutes means by which the lamp casing may be manipulated. Said 90 neck may be brazed or otherwise fixed to the lamp casing. The rear end of the neck 33 is closed by a cap 35, the flange or rim 36 of which fits in overlapping engagement with the rear, expanded end of said neck. 95 100 105

Interposed between the rear central portion of the reflector and said pin 26, and surrounding the flange 24 of the reflector, is a spiral expansion spring 38 which tends to force the socket sleeve 22, and the lamp 110

carried thereby, rearwardly with respect to the reflector. Engaging the pin 26 on the rear side thereof, and opposing the action of the spring 38 to thus force the lamp and its socket sleeve rearwardly, is an adjusting device designated as a whole by 39. Said adjusting device comprises a flat ring 40 which is made of a diameter to engage the said pin 26 at its ends, and a rearwardly extending fork member, the arms 41 of which are turned laterally at their forward ends 42 and are fixed to the rear face of the ring in any suitable manner, as by brazing or soldering. Said fork arms terminate in a rearwardly directed threaded shank 44.

The arms 41 of the fork members extend through the neck 33 and are suitably guided therein, and the threaded shank 44 extends through a central opening in the cap 35 and receives a threaded adjusted nut 45 that bears against and is swiveled to the rear end of said cap. The arms of said adjusting fork members are guided in endwise movement between the wall of the neck 33 and a bushing 47 within said neck, said bushing being of a diameter to closely embrace the switch device 31 and to confine it therein. The walls of said bushing, at said fork arms, are provided with longitudinal, convex depressions, indicated at 48 in Figs. 2, 3 and 5, to receive the fork arms 41, and the fit between the bushing and neck is such that the parts are frictionally held from shifting. The threaded connection of the nut 45 with the shank 44 of the adjusting member 39 acts, through the pin 26 to force the socket sleeve and the lamp carried thereby forwardly against the action of the spring 38, and when proper focal adjustment of the lamp is attained the nut 45 serves to lock the parts in fixed adjustment.

I claim as my invention:—

1. Focal adjusting means for lamps comprising, in combination, a lamp casing, a reflector therein having an axial guide, a lamp socket slidable in said guide, a neck connected to said casing in axial alinement with said guide, a pin extending transversely through said socket, a spring acting on said pin tending to move the socket outwardly, a ring member bearing on said pin, and a screw threaded member having fork arms acting in opposition to said spring, the terminals of the arms bearing against said ring 55 on diametrically opposite sides thereof.

2. Focal adjusting means for lamps comprising, in combination, a lamp casing, a reflector therein having an axial guide, a lamp socket slidable in said guide, a neck connected to said casing in axial alinement 60 with said guide, a spring acting to move the lamp socket outwardly, a switch carrying bushing in said neck, and a screw threaded device acting at its inner end against said socket in opposition to said spring and embracing fork arms which are guided between said bushing and neck and terminate in a screw threaded terminal, and a nut threaded to said terminal and engaging said neck.

3. Focal adjusting means for lamps comprising, in combination, a lamp casing, a reflector therein having an axial guide, a lamp socket slidable in said guide, a neck connected to said casing in axial alinement with said guide, a pin extending transversely 70 through said socket, a spring interposed between said pin and the reflector, a ring opposed to said spring and bearing on said pin, and an adjusting member connected to said ring and having guiding engagement in 75 said neck, said adjusting member embracing a threaded shank and a nut threaded to the shank and engaging on the wall of the neck.

4. Focal adjusting means for lamps comprising, in combination, a lamp casing, a 85 reflector therein having an axial guide, a lamp socket slidable in said guide, a neck connected to said casing in axial alinement with said guide, a pin extending transversely through said socket, a spring interposed between said pin and the reflector, a ring opposed to said spring and bearing on said pin, an adjusting member connected to 90 said ring and having guiding engagement in said neck, said adjusting member embracing a threaded shank and a nut threaded to the shank and engaging on the wall of the neck, 95 and a guide in the neck for said adjusting member, embracing a bushing fitting said neck and having a longitudinal groove to receive said member.

In testimony whereof I claim the foregoing as my invention, I hereunto append my signature in the presence of two witnesses at Chicago, Illinois, this 22nd day of October, 105 1917.

ERNST G. K. ANDERSON.
